UNITED STATES PATENT OFFICE.

HENRY WESTLAKE ANGUS AND ABEL WATTERS CHAMBERLIN, OF NORTH BAY,
ONTARIO, CANADA.

TOY BUILDING CONSTRUCTION.

1,240,807.

Specification of Letters Patent. Patented Sept. 25, 1917.

Application filed July 8, 1916. Serial No. 108,251.

To all whom it may concern:

Be it known that we, HENRY WESTLAKE ANGUS and ABEL WATTERS CHAMBERLIN, both subjects of the King of Great Britain, and residents of North Bay, in the Province of Ontario, Dominion of Canada, have invented certain new and useful Improvements in Toy Building Construction, of which the following is the specification.

10 This invention relates to improvements in toy building construction, and the objects of the invention are to permit of several articles of characteristic design being readily constructed, to render the several parts or 15 members compact so that when packed they will occupy a minimum of space convenient for shipping, to increase the efficiency and serviceability, to cheapen the cost of construction and generally to adapt the several 20 parts to better perform the functions required of them. With the above and other objects in view the invention consists essentially of the improved construction particularly described and set forth in the following specification and accompanying drawings forming part of the same.

In the drawings,

Figure 1 is a perspective view of a field gun embodying the present invention.

30 Fig. 2 is a perspective view of a chair embodying the present invention.

Fig. 3 is a perspective view of the lateral walls of a box embodying the present invention.

35 Fig. 4 is a perspective view of a wheel hub.

Fig. 5 is a perspective view of a building strip or block.

40 Fig. 6 is a perspective view of a spindle or shaft.

Like characters of reference refer to like parts in the several figures.

Referring to the drawings, A represents a wheel hub provided with an orifice 10 there-through adapted to rotatably engage with the shaft or spindle B, the periphery of the hub being provided with a plurality of transversely extending slots 11, the object of which will be made clear hereafter.

50 C represents a building strip which may be made of suitable stock lengths provided at the ends with a plurality of longitudinally extending slots 12 subdividing the said ends into a plurality of fingers 13, while

intermediate of the length of the said strips 55 slots 14 are provided in the opposite lateral faces of the same.

In using the building strips C, the hub A and the spindle B in a construction requiring the use of wheels, the fingers 13 of one 60 set of building strips C are engaged with the slots 12 in the hub and when the necessary number of strips have been thus arranged to form the spokes, the periphery of the wheel is completed by building strips of 65 a similar construction to those used in forming the spokes but of a shorter length and arranged so that the fingers 13 will engage with the slots 12 in the outer end of the said spokes.

70 In an ordinary construction not requiring the use of wheels, the building strips C are so arranged that the fingers 13 engage with the slots 12 or 14 of adjacent strips, and the construction is proceeded with until it assumes the desired formation. It will be understood that in using building strips of 75 this description that a great deal of ingenuity may be shown by the user.

80 In Figs. 1, 2 and 3, this is particularly emphasized and illustrates a very wide range of adaptability of the building strips, hub and spindle.

85 It will be understood that although we have only illustrated three of the articles which may be assembled from these building strips C, hub A and shaft B, quite a number of such articles, including airships, bridges, windmills, aeroplanes, beds, trucks and the like may be similarly constructed.

90 The several members enumerated are made of timber so that the cost of the building construction is extremely low, and should any of the strips become broken they may be readily replaced at a minimum of cost.

95 As many changes could be made in the above construction and many apparently widely different embodiments of my invention, within the scope of the claim, constructed without departing from the spirit 100 or scope thereof, it is intended that all matter contained in the accompanying specification and drawings shall be interpreted as illustrative and not in a limiting sense.

105 What we claim as our invention is:

A toy building construction comprising a plurality of strips each being formed of substantially rectangular shape provided with

a plurality of elongated parallel sided slots in the ends subdividing the said ends into a plurality of fingers, and having transverse parallel slots in the lateral faces intermediate of the length of the said strips, the said fingers and slots of adjacent strips being designed to be frictionally engaged, a hub having a plurality of longitudinal grooves in the periphery thereof designed to frictionally engage with the fingers of the strips,

and a spindle adapted to engage with the hub.

In witness whereof we have hereunto set our hands in the presence of two witnesses.

HENRY WESTLAKE ANGUS.
ABEL WATTERS CHAMBERLIN.

Witnesses:

ELIZABETH WILSON,
R. Y. ANGUS.
